UNITED STATES PATENT OFFICE

168,816

CLASP FOR NECKLACES AND THE LIKE

Frank W. Young, East Orange, N. J., assignor to Illinois Watch Case Co., a corporation of Illinois

Application April 4, 1951, Serial No. 14,706

Term of patent 14 years

(Cl. D17—3)

To all whom it may concern:

Be it known that I, Frank W. Young, a citizen of the United States, residing at East Orange, in the county of Essex and State of New Jersey, have invented a new, original, and ornamental Design for a Clasp for Necklaces and the like, of which the following is a specification, reference being had to the accompanying drawing, forming part thereof.

I claim:

The ornamental design for a clasp for necklaces and the like, as shown.

FRANK W. YOUNG.
